(57) **CLAIM**

The ornamental design for a bait net casting device design, as shown and described.

DESCRIPTION

FIG. 1 is an isometric view of a bait net casting device showing our new design;

FIG. 2 is a front elevational view of FIG. 1;

FIG. 3 is a rear elevational view of FIG. 1;

FIG. 4 is a right elevational view of FIG. 1;

FIG. 5 is a left side elevational view of FIG. 1;

FIG. 6 is a top plan view of FIG. 1;

FIG. 7 is a bottom plan view of FIG. 1;

FIG. 8 is an operational view showing the net being thrown where the wire extends illustrating the elasticity of netting;

FIG. 9 is another operational view where the user pulls the netting thereby the net; and,

FIG. 10 is a further operational view where the netting is fully contracted.

The broken lines are included for the purpose of illustrating features of the bait net casting device design that form no part of the claimed design.
